[57] ABSTRACT

Regenerative coke oven batteries have heating chambers on opposite sides of the coking chamber and the heating chambers have parallel spaced heating walls with a plurality of spaced flue walls extending transversely between and connected to the heating walls. The flue walls form a series of vertical flues in the heating chambers. Combustion of the gaseous fuels takes place in alternate flues and the gaseous products of combustion are directed to flow downwardly in the adjacent flue for further transfer of heat from the gases to the heating walls. The flue walls are formed of individual bricks in parallel courses with the bricks bonded to adjacent bricks. Cylindrical passageways are formed in the bricks in spaced relation to the edges of the bricks, particularly the horizontal edges so that the bond between adjacent bricks is not interrupted by the horizontal passageways. The flow of gases through the passageways is controlled by slab-like dampener bricks. The bricks are positioned in a generally vertical position parallel to the flue wall and are arranged to pivot in one direction into abutting relation with the flue wall and in overlying relation with the passageways to thereby control the flow of gas therethrough.

**APPARATUS FOR CONTROLLING THE FLOW OF
GAS BETWEEN FLUES IN THE HEATING
CHAMBERS OF A REGENERATIVE COKE OVEN**

BACKGROUND OF THE INVENTION

1. Field of the Invention

This invention relates to apparatus for controlling the flow of gas between flues in the heating chambers of a coke oven and more particularly to cylindrically shaped passageways in the flue wall and pivotable dampener bricks.

2. Description of the Prior Art

Regenerative coke oven batteries have a pair of heating chambers on opposite sides of the coke oven chamber. The heating chambers have transverse flue walls that divide the heating chamber into a plurality of separate vertical flues. The flues in the respective heating chambers on opposite sides of the coke oven chamber may be connected in a number of different fashions to circulate the products of combustion from the "on" flue or flues to the "off" flue or flues. The hairpin type oven, for example, connects one flue with the adjacent flue in the same heating chamber so that the "on" flue is adjacent to the "off" flue and the products of combustion flow upwardly through the "on" flue, through a horizontal passageway or passageways into the adjacent "off" flue and then downwardly through the "off" flue to the regenerator therebelow. The hairpin type flues are illustrated and described in U. S. Pat. Nos. 2,845,385 and 3,431,177.

As is illustrated in U. S. Pat. No. 2,845,385, passageways are provided in the flue walls adjacent the base of the heating wall to permit recirculation of a portion of the products of combustion from the "off" flue to the "on" flue to thereby dilute the combustion gases in the "on" flue. It is desirable for optimum operation to control the flow of combustion gas through the respective passageways between adjacent flues. In the past, the flow of gas through the passageways was controlled by means of sliding bricks similar to the sliding bricks illustrated in U. S. Pat. No. 2,100,762. The bricks are moved horizontally by sliding on a support means into the desired position within the respective flues by means of a long rod that extends down the flue from the top of the oven.

The known sliding bricks are relatively heavy and are difficult to move with the long adjusting rod. Recently, ovens having a height of 20 feet or more increase the above discussed problems because of the added length of the actuating rods. There is a need for apparatus to easily control the flow of gases through the passageways in the flue wall.

In the past two rectangular openings or passageways have been provided in the base of the flue wall through which a portion of the products of combustion flow from one flue into the adjacent flue. The brick bond over the base of the heating flue is interrupted by these two relatively large openings or passageways and this substantially weakens the flue wall structure. The weakening is of particular importance in high ovens with large capacity where premature damage to the flue walls appears at the interruption in the brick bond. There is a need therefore for passageways through the flue wall that efficiently convey a portion of the products of combustion from one flue to the other and

do not substantially weaken the structure of the flue wall.

SUMMARY OF THE INVENTION

The hereinafter described invention is directed to a damper for controlling the flow of gas through passageways in a coke oven flue wall and includes a dampener brick with a generally rectangular configuration in section. The dampener brick has a front wall, a rear wall, a top wall and a bottom wall. The length between the top and bottom walls of the dampener brick is substantially greater than the thickness between the front and rear walls. A support means is provided for the dampener brick adjacent to the vertical flue wall. The dampener brick bottom wall is positioned on the support means in spaced relation to the flue wall and extends upwardly therefrom. The dampener brick is arranged to pivot on the support means in a first direction to position a portion of the front wall in abutting relation with the flue wall and overlying at least one of the gas flow passageways to control the flow of gas therethrough. The dampener brick is pivotable in a second direction with the front wall in spaced relation to the flue wall to permit relatively unobstructed flow of the gas through the horizontal passageways.

The passageways in the flue wall extend through the bricks forming the flue wall and are spaced from the edge portions of the bricks so that the bond between adjacent bricks remains uninterrupted. It is preferred that the passageways have a generally cylindrical configuration and four passageways are provided in each of the bottom two courses of brick. The dampener bricks are easily pivoted from an open to a closed position by the pivot arrangement and the cylindrical passageways eliminate the inherent weakness in the flue walls caused by the interruption in the brick bond between adjacent courses of brick.

The principal feature of this invention is to provide a damper brick for controlling the flow of gas through passageways in the coke oven flue wall that is moved from an open to a closed position by a pivoting action.

Another feature of this invention is to provide a flue wall having passageways therethrough that do not interrupt the bond between adjacent brick courses.

These and other features and advantages of this invention will be more completely disclosed and described in the following specification, the accompanying drawings and the appended claims.

BRIEF DESCRIPTION OF THE DRAWINGS

FIG. 1 is a fragmentary sectional view in elevation of a pair of adjacent flues with a flue wall therebetween having cylindrical passageways therethrough and the improved dampener brick.

FIG. 2 is a view in vertical section taken along the line II—II of FIG. 1 illustrating in elevation the cylindrical passageways through the flue wall.

**DESCRIPTION OF THE PREFERRED
EMBODIMENTS**

Referring to the drawings there is illustrated a heating chamber generally designated by the numeral 10 that has a pair of spaced heating walls 12 and 14. A flue

wall 16 extends transversely between and is connected to the heating walls 12 and 14. The flue wall 16 forms a pair of vertical flues 18 and 20 in the heating chamber 10 and other flue walls 22 and 24 extend between the heating walls 12 and 14 to form other flues within the heating chamber 10.

Vertical fuel supply passageways 26 and 28 are provided for the respective flues 18 and 20 to supply the gaseous fuel for combustion within the respective flues. Other vertical passageways 30 and 32 are provided in the flues 18 and 20 to supply air to the "on" flue and withdraw gaseous products of combustion from the "off" flue. For optimum combustion within the "on" flue, it is desirable at times to divert a portion of the gaseous products of combustion from the "off" to the "on" flue to dilute the gaseous mixture within the "on" flue.

The heating chamber has a base portion 34 on which the flue wall 16 is supported. The flue wall 16 is formed from a plurality of separate bricks as, for example, bricks 38, 40 and 42 in FIG. 2, to form the bottom course of bricks in the flue wall 16. A second course of bricks 44, 46 and 48 is positioned on the first course comprising bricks 38, 40 and 42. As is illustrated in FIG. 1, a plurality of other courses of bricks are positioned in overlying relation to each other to form the flue wall 16. The individual bricks 38, 40 and 42 are bonded to each other as are the bricks 44, 46 and 48. Similarly the overlying courses of bricks are also bonded to each other.

It should be noted in FIG. 2 that the upper edges of the bricks 38, 40 and 42 abut the lower edges of bricks 44, 46 and 48 so that the bond between the first, second and third courses of bricks remains uninterrupted. To convey the gaseous products of combustion from one flue to the adjacent flue there are provided cylindrical passageways 50, 52, 54 and 56 in the first course of brick in the flue wall 16. Additional cylindrical passageways 58, 60, 62 and 64 extend through the bricks in the second course of bricks in the heating wall 16. With this arrangement the cylindrical passageways are formed in the bricks and are spaced from the upper and lower faces or edges of the bricks so that the bond between adjacent bricks remains unobstructed and the flue wall 16 is not weakened by the horizontal passageways extending therethrough.

In order to control the flow of gas through the passageways there are provided a plurality of slab-like dampeners generally designated by the numeral 66. The slab-like dampeners have a front wall 68, a rear wall 70, a bottom wall 72 and a top wall 74. The bottom wall 72 has an arcuate configuration that is positioned in a mating arcuate recess 76 in the heating chamber base portion 34. The arcuate recess 76 is spaced from the vertical flue wall 16 and is parallel thereto.

The slab-like dampener brick front wall 68 has an angularly diverging portion 78 that is arranged to abut the surface of the flue wall 16 when it is pivoted to a closed position as is illustrated in phantom lines in FIG. 1.

The dampener brick 66 may be easily pivoted in a first direction by a conventional rod member to a position where the diverging surface 78 of front wall 68 abuts the flue wall 16 and is in overlying relation with the passageways 62 and 54 to control the flow of gas therethrough. When it is desired to permit an un-

restricted flow of gas through the passageways 62 and 54, the slab-like dampener brick 66 is pivoted in a second direction until the rear wall 78 abuts a stop member 80 formed in the conduit 32 as is illustrated in FIG. 1.

From the above description it will be apparent that it is now possible to easily open and close the passageways in the vertical flue wall 16 without moving massive rectangular dampener bricks as has been the practice in the past. Also, with the cylindrical passageways through the flue wall, the bond between the courses of brick remains uninterrupted so that the flue wall is not weakened by the horizontal passageways therethrough.

According to the provisions of the patent statutes, I have explained the principle, preferred construction and mode of operation of my invention and have illustrated and described what I now consider to represent its best embodiments. However, I desire to have it understood that, within the scope of the appended claims, the invention may be practiced otherwise than as specifically illustrated and described.

I claim:

1. A damper for controlling the flow of gas through passageways in a coke oven flue wall comprising, a damper brick having a generally rectangular configuration in section with a front wall, a rear wall, a top wall and a bottom wall, said damper brick having a length between said top and bottom walls substantially greater than the thickness between said front and rear walls, a vertical flue wall between a pair of adjacent flues, horizontal passageways in said flue wall for the flow of gas therethrough from one flue to the other flue of said pair of adjacent flues, a support means for said damper brick positioned adjacent to said vertical flue wall, said damper brick bottom wall positioned on said support means in spaced relation to said flue wall, and said damper brick extending upwardly from said support means and arranged to pivot on said support means in a first direction to position a portion of said front wall in abutting relation with said flue wall and overlying at least one of said gas flow passageways to control the flow of gas therethrough and in a second direction with said front wall in spaced relation to said flue wall to permit relatively unobstructed flow of gas through said passageways.

2. A damper for controlling the flow of gas through passageways in a coke oven flue wall as set forth in claim 1 in which,

said bottom wall has an arcuate configuration in vertical section forming an arcuate bottom wall, said support means having a transverse arcuate recessed portion extending substantially parallel to said flue wall, said arcuate bottom wall positioned in said arcuate recessed portion for pivotal movement of said damper brick therein.

3. A damper for controlling the flow of gas through passageways in a coke oven flue wall as set forth in claim 2 in which,

said transverse recessed portion in said support means is spaced from said flue wall.

4. A damper for controlling the flow of gas through passageways in a coke oven flue wall as set forth in claim 1 in which,

said support means includes a support for said damper brick rear wall to limit the pivotal movement of said damper brick in said second direction and maintain said damper brick in a generally upright position while said damper brick front wall is in spaced relation to said flue wall.

5. A damper for controlling the flow of gas through passageways in a coke oven flue wall as set forth in claim 1 in which,

said front wall has an upper diverging portion extending angularly toward said rear wall, said upper diverging portion arranged to abut said flue wall.

6. A damper for controlling the flow of gas through passageways in a coke oven flue wall as set forth in claim 5 in which,

said passageways in said flue wall have a generally cylindrical configuration and extend horizontally through the bricks forming said flue wall.

7. In a regenerative coke oven the combination comprising,

a heating chamber having a pair of spaced parallel heating walls,
a flue wall extending transversely between said heating walls and connected thereto,
said flue wall formed from a plurality of parallel courses of individual bricks bonded to adjacent bricks in said wall, and
certain of said bricks having horizontal passageways therethrough between adjacent flues spaced from the edge portions of said bricks so that said bond between said adjacent bricks remains uninterrupted by said passageways.

8. A regenerative coke oven as set forth in claim 7 in which said passageways extend through the bricks in the two bottom courses of brick in said flue wall.

9. A regenerative coke oven as set forth in claim 8 in which said passageways have a generally cylindrical configuration.

10. A regenerative coke oven as set forth in claim 9 in which each of said two bottom courses of brick in said flue wall have four passageways with a generally cylindrical configuration.
